UNITED STATES PATENT OFFICE

2,246,434

AUTOMATIC MAGNETIC KEY SUSTAINING
DEVICE FOR KEYBOARD MUSICAL IN-
STRUMENTS

Joseph A. Dezso, South Bend, Ind.

Application February 29, 1940, Serial No. 321,589

7 Claims. (Cl. 84—441)

This invention relates to an improved device for use on musical instruments of the keyboard type for sustaining notes or chords and having magnetic means for engaging elements carried by the instrument keys for retaining the keys in a depressed position until actuated by other key or keys of the instrument to thereby sustain a note or chord after the fingers have been removed from the keys striking such note or chord.

Another object of the invention is to provide a device of the character described including an electromagnet connected to a source of electric current and energized thereby for attracting metallic elements secured to and depending from the keys of a musical instrument for holding the keys in a depressed position, said electromagnet being connected in circuit with a plurality of electrical switches each of which is adapted to be actuated by a partial depressing of one of the keys for opening the switch to interrupt the circuit to the electromagnet and to thereby release other keys which may be held depressed.

Still another aim of the invention is to provide a novel form of electric switch and means for actuating the switch whereby the switch will be opened by partially depressing a key carrying the aforementioned means and released by said means to return to a closed position when the key is fully depressed, said means being retractible to pass the switch without affecting its closed position when the key is returned to a normal, raised position.

Other objects and advantages of the invention will hereinafter become more fully apparent from the following description of the drawings, which illustrate a preferred embodiment thereof, and wherein:

Figure 1 is a transverse sectional view taken through a portion of the framework of a keyboard type musical instrument, such as a piano, and showing two of its keys in elevation and the invention, associated therewith and shown partly in elevation and partly in cross section,

Figure 2 is a horizontal sectional view taken substantially along the plane of the line 2—2 of Figure 1,

Figure 3 is a view similar to Figure 1 showing one of the keys in a partly depressed position for interrupting the electric circuit to the electromagnet.

Figure 4 is a view similar to Figure 3 showing a key in a fully depressed position with the switch in a released and closed position to complete the circuit to the electromagnet.

Figure 5 is a longitudinal vertical sectional

view taken substantially along the plane of the line 5—5 of Figure 1.

Figure 6 is a perspective view of the insulating block in which the switches and electromagnet are mounted;

Figure 7 is a similar view of one of the supporting hangers or brackets;

Figure 8 is a similar view of one of the metallic members which are adapted to be attracted by the electromagnet, and

Figure 9 is a diagrammatic view of the circuit in which the electromagnet and switches are connected.

Referring more particularly to the drawings wherein like reference characters designate like or corresponding parts throughout the different views, for the purpose of illustration, 10 designates generally a portion of the framework of a keyboard type musical instrument such as a piano having a keyboard, designated generally 11 with the long natural tone keys 12 and the short, sharp and flat tone keys 13, which parts are shown merely to illustrate the application of the tone sustaining means, designated generally 14 and comprising the invention, which will hereinafter be described.

The tone sustaining attachment 14 includes a block 15 of insulating material which is mounted in the frame 10 longitudinally thereof, beneath the keys 12 and slightly beyond the free ends of the keys 13, as best seen in Figures 1, 3 and 4. Referring to Figure 6, the block 15 is provided with a plurality of spaced recesses 16 which open outwardly of its top and which extend downwardly to adjacent its bottom to form a bottom or lower portion 17 and a plurality of walls 18 disposed between the recesses 16. The bottom portions of the outer ends of the walls 18 are cutaway as indicated at 19 to receive a bar of metal 20 which extends substantially the length of the insulated block 15 and which is supported by the lower portion or bottom 17, as best seen in Figures 1, 3 and 4. The adjacent recesses 16 are connected by slots 21 which extend diagonally through the upper portions of the walls 18. A contact element 22 is disposed in each of the recesses 16 adjacent its upper forward portion and is supported by a fastening 23 mounted in an adjacent wall 18 and to which is connected 50 an arm 24 which extends from the contact element 22 to thereby fixedly support the contact elements 22 relatively to the block 15.

As best seen in Figures 1, 3 and 4, an arm 25 is disposed in each of the recesses 16 and pivotally connected at one end by means of a pin 26 to a

wall 18. The pin 26 extends into and engages a recess portion 21' of the slot 21, for a purpose which will hereinafter become apparent. Adjacent their outer free ends and on their upper sides, the arms 25 are each provided with a contact element 27. A leaf spring 28 is secured at one end to a corresponding side of each of the walls 18 with its free end extending upwardly and forwardly therefrom to engage beneath the pivoted arm 25 mounted on the same wall 18 to urge the free end of said arm upwardly to cause its contact element 27 to engage the contact element 22 mounted on the same wall 18, as best seen in Figures 1 and 4. As seen in Figure 2, each of the contact elements 22 is connected by means of a conductor wire 29 which extends through a slot 21, to the pivot pin 26 on the wall 18 directly to the right of the wall 18 on which the contact member 22 is mounted, so that each contact member 22 is connected by a wire 29 to the next adjacent pivot pin 26 to its right, as illustrated diagrammatically in Figure 9, and as the arms 25 form conductors between the pivot pins 26 and the contact points 27 these parts are all connected together. Each pair of contact elements 22 and 27, the arm 25 associated therewith, and its pivot pin 26 combine to form an electric switch, designated generally 30. As seen in Figure 9, a circuit is shown wherein the switches 30 are all connected in circuit with one another and with the electromagnet 20 which circuit includes a conductor 31 which extends from a source of electrical current through a transformer 32 by means of which the current is stepped down, thence to one end of the bar 20 forming the electromagnet. A conductor 33 extends from the opposite end of the bar 20 to the pivot pin 26 of the last switch 30 at one end of the insulating block 15. The other switches 30 are connected to one another, as heretofore explained, by the conductors 29 and the contact element 22 of the switch 30 at the opposite end of the block 15 is connected to a conductor 34 which extends back through the transformer 32 and back to the source of electrical current, not shown, to ground the circuit. Conductor 34 is preferably provided with a manually controlled switch 35 by means of which the circuit may be opened when the instrument on which the invention 14 is mounted is not in use and for playing the instrument without employing the attachment 14.

A bracket or hanger 36 has one end 37 provided with an elongated slot 38 to receive a screw fastening 39 for securing it to the underside of a key 12 or 13. A hanger 36 is thus secured to each of the keys 12 and 13 and said hangers are disposed in substantially a straight line with those secured to the keys 13 disposed adjacent their free ends and those secured to the longer keys 12 disposed intermediate of their ends. By means of the slots 38, the brackets or hangers 36 may be adjusted longitudinally of the keys 12 and 13 to move them toward or away from the block 15 for a purpose which will hereinafter be explained. The opposite, depending ends 40 of the hangers 36 are disposed substantially at right angles to the ends 37 and are provided, adjacent their lower ends, with longitudinal slots 41 and adjacent their opposite ends with openings 42. A metallic member 43 is secured to each of the ends 40 by means of a screw fastening 44 which extends through the slot 41 into a threaded opening 45 in the member 43. Slots 41 provide means whereby the members 43 may be adjusted longitudinally of the ends 40. A leaf spring 46 is

secured at one end by means of a fastening 47, which engages the opening 42 to each of the ends 40. Leaf springs 46 project downwardly and outwardly from the brackets or hangers 36 and are adapted to be disposed with their free ends directly above the free ends of the arms 25 of the switches 30 when the keys 12 and 13 are in their normal, substantially horizontal positions.

Assuming the switch 35 to be closed, a key 12 or 13 or a group of said keys are depressed by the fingers of the player and as the keys begin to move downwardly the springs 46 of the hangers 36, carried by said keys, will depress the arms 25 with which the springs 46 are associated to break the connection between the contacts 22 and 27 of the switches 30 of which said arms 25 form a part. After such keys 12 and 13 have moved past a partially depressed position, as seen in Figure 3, the springs 46 will be swung out of engagement with the free ends of the aforementioned arms 25 to release said arms to allow the contacts 22 and 27 of their switches 30 to return to a closed position to complete the circuit, as seen in Figure 9, to cause the electricity passing through the bar 20 to magnetize the bar to cause it to function as an electromagnet for attracting the metallic members 43 of the depressed keys 12 and 13 to hold these keys in a depressed position, as seen in Figure 4, to thereby sustain the notes or chords struck by said keys. When another key 12 or 13 or a group of said keys are pressed down, their springs 46 will similarly engage and depress the arms 25 associated therewith. As soon as any one of the other arms 25 is moved downwardly to cause its contact point 27 to move out of engagement with its contact point 22 the circuit through the electromagnet 20 will be broken to demagnetize it to release the members 43 which have been held attracted thereby so that their keys 12 and 13 may return to a fully raised position with their springs 46 retracting to pass over the free ends of the arms 25 with which they are associated. It will thus be seen that any one of the keys 12 or 13 may be partially depressed for releasing any number of the keys which are held in a depressed position after which the partially depressed key may be released to return to a raised position. It is to be understood that a switch 30 is associated with each of the hangers 36 or brackets 36, one of which is connected to each of the keys 12 and 13. The brackets or hangers 36 may be adjusted, as heretofore explained, relatively to the keys 12 and 13 for properly positioning the springs 46 for engagement with the arms 25 and the members 43, which are disposed transversely of the bracket ends 40 may be adjusted longitudinally thereof for properly positioning them relatively to the bar or electromagnet 20.

Various modifications and changes are contemplated and may obviously be resorted to as only a preferred embodiment of the invention has been disclosed.

I claim as my invention:

1. An attachment for keyboard type instruments comprising a block of insulating material mounted in an instrument frame, an electromagnet disposed in said block and connected to a source of electrical current, hangers connected to and depending from each of the keys of the instrument and provided with metallic blocks arranged for attraction by said magnet when their supporting keys are in a fully depressed position, a plurality of switches mounted in said insulated block and connected in circuit with said magnet,

and a spring finger attached to each of said hangers, and extending outwardly and downwardly therefrom, for engaging and opening the switches when the keys are in a partially depressed position to break the circuit to the magnet.

2. An attachment for keyboard type musical instruments comprising electromagnetic means connected to a source of electrical current and disposed within the frame of a musical instrument and beneath its keyboard, hangers, having metallic members secured to their depending ends, connected to and depending from the keys of the keyboard, said metallic members being arranged to be attracted by the electromagnetic means when their supporting keys are in a depressed position, a plurality of switches connected in circuit with said electromagnetic means, and a spring finger attached to each of said hangers, and extending outwardly and downwardly therefrom, for depressing and opening the switches, when the keys are in a partially depressed position, whereby said electromagnetic means will be deenergized by partially depressing any one of the keys.

3. A tone sustaining attachment for keyboard type musical instruments comprising an electromagnet connected to a source of electric current, metallic members supported by and depending from the keys of a musical instrument and movable, by depressing the keys, into a position adjacent to the electromagnet to be attracted thereby to retain the depressed keys in a depressed position, a plurality of switches connected in circuit with said electromagnet, and a spring finger extending downwardly and outwardly from each of said keys, for engaging and opening the switches when the keys are in a partially depressed position for deenergizing the electromagnet.

4. A tone sustaining attachment for keyboard type musical instruments comprising a block of insulating material mounted in the frame of a musical instrument and beneath the keyboard thereof, an electromagnet mounted in said block and connected to a source of electrical current, a plurality of electric switches mounted in spaced

apart relationship relatively to each other in said insulated block, said switches being connected in circuit with said electromagnet, hangers secured to and depending from the keys of the instrument, a metallic member connected to the depending end of each of said hangers, said metallic members being arranged to be attracted by the electromagnet when their supporting keys are in a fully depressed position to retain said keys depressed, and a spring finger attached to and projecting downwardly and outwardly from each of said hangers, for engaging and opening a switch when its supporting key is partially depressed for interrupting the circuit to the electromagnet for releasing the depressed keys.

5. A device as in claim 4, said electric switches each including a fixed contact point and a pivotally mounted contact element having a contact point for engaging the fixed contact point, spring means for normally raising said pivotally mounted contact element for closing the switch, and said contact elements being engageable by said spring fingers, when the keys are partially depressed, for interrupting the circuit, said spring fingers being movable out of engagement with the pivotally mounted contact elements when the keys are moved to a fully depressed position.

6. A device as in claim 4, said switches each including a pivotally mounted contact element, to be engaged by a spring finger when its supporting key is partially depressed to open the circuit to the magnet, said spring fingers moving out of engagement with said contact elements when the keys are fully depressed to permit the switches to return to a closed position for energizing the magnet, and said spring fingers being retracted by said contact elements to move past said elements when the keys are returned to a raised, normal position.

7. A device as in claim 4, each of said hangers being provided with means for longitudinally adjusting it relatively to its supporting key for moving the hangers toward and away from the insulated block, and means, on said hangers, for longitudinally adjusting said metallic members relatively thereto.

JOSEPH A. DEZSO.
